UNITED STATES PATENT OFFICE.

ERNST G. ANDERSON, OF CRANFORD, NEW JERSEY.

ADJUSTING DEVICE FOR THE NOTE-SHEETS OF SELF-PLAYING MUSICAL INSTRUMENTS.

1,134,986.

Specification of Letters Patent. Patented Apr. 13, 1915.

Application filed May 9, 1910. Serial No. 560,189.

To all whom it may concern:

Be it known that I, ERNST G. ANDERSON, a citizen of the United States, residing at Cranford, in the county of Union and State 5 of New Jersey, have invented certain new and useful Improvements in Adjusting Devices for the Note-Sheets of a Self-Playing Musical Instrument, of which the following is a specification, reference being had therein 10 to the accompanying drawings.

This invention relates to an adjusting device for the note sheet of a self playing musical instrument.

The object of the invention is to provide 15 mechanical means for maintaining the proper relation between the traveling note sheet and the tracker bar or other co-operating part of the instrument.

To this end it is a further object of the 20 invention to provide positively actuated means for restoring the note sheet to its normal position, *i. e.*, its true course, when it has been diverted therefrom; to provide a shifting device for so adjusting the sheet 25 which shall be controlled by the lateral movement of the sheet itself; and further, to provide such a device which shall be simple in its construction and operation and not liable to be broken or so disarranged as to 30 render the same inoperative.

In the accompanying drawings, Figure 1 is a front elevation, partially in section, of 35 an apparatus embodying my invention; Fig. 2 is a detail view of the circuit breakers and closers, showing their arrangement relative to the tracker board; Fig. 3 is a similar view of a modified form of the invention; Fig. 4 is a sectional view, taken transversely to the tracker bar in that form of the invention 40 shown in Figs. 1 and 2; Fig. 5 is an end elevation of one of the sheet rollers showing a modified form of circuit breaker and closer mounted thereon; and Fig. 6 is a side elevation of the same.

45 In these drawings I have illustrated one embodiment of my invention. The form here shown is particularly designed for use in connection with an electrically operated organ, but the invention is well adapted for 50 use with any self playing musical instrument which employs a traveling note-sheet. The instrument itself may be of any desired construction and forms no part of the present invention. I have, therefore, shown only 55 so much of the instrument to which the invention is applied as is necessary to a com-

plete understanding of the operation of the invention.

The reference numeral 1 indicates a portion of the frame of the instrument and has 60 mounted thereon two rollers 2 and 3 arranged on opposite sides of the tracker bar 4. One of these rollers, in the present instance, the upper roller 2, has the note-sheet 5 wound thereon and is removably supported in the frame 1 so that both the roller and the note-sheet 65 can be removed in the usual manner. The other roller 3 serves as a take-up roller and is operated to unwind the note-sheet, draw the same across the tracker bar and support it. This roller may be supported in the frame 1 in any suitable manner. As here 70 shown it is mounted on adjustable pintles 6 which are screw-threaded into bushings 7 mounted in the side members of the main 75 frame. The roller 3 is rotated in the usual manner, and, as the manner of this rotation does not enter into the present invention, the mechanism for rotating the same is neither shown nor described. As stated, the 80 upper roller 2 is removably mounted in the frame 1, and, while the roller may be supported in any suitable manner, I have here shown the same as provided with short shafts, 8 and 9, extending beyond the opposite 85 ends thereof.

The shaft 8 constitutes a bearing block 90 and has formed therein a recess to receive the point of a spring-pressed pin 10 which is slidably mounted in a sleeve 11 supported by the frame 1. A spring 12 is coiled about the pin 10 within the sleeve 11 and bears at one end against the end of the sleeve and at the other end against a stop 13 secured to the pin 10. This spring tends to press the 95 pin toward the roller and to hold the same in engagement with the bearing in the end of the shaft 8. The shaft 9 at the opposite end of the roller 2 is detachably connected to the roller by means of a coupling 15. The 100 shaft 9 is slidably mounted in a bushing 16 supported in the adjacent member of the frame 1, extends some distance beyond that frame member and has rigidly secured thereto at a point beyond the frame member a 105 grooved collar 17. The groove of the collar 17 is arranged to receive the arms of a yoke 18 carried by the lower end of a lever 19 which is pivotally mounted at a point between its ends upon a bracket 20 mounted 110 on the main frame. It will be noted that by moving the lever 19 about its pivotal center

the roller 2 will be adjusted longitudinally and the note-sheet 5 will be shifted laterally. It will be understood that the mechanism above described for shifting the note-sheet laterally is shown and described for the purpose of illustration only and that any suitable mechanism may be employed for this purpose.

Means are provided whereby the movement of the shifting device is controlled by the lateral displacement of the note-sheet 5. For this purpose a suitable operating mechanism is connected to the lever 19 and the actuating power for this operating mechanism is controlled by electro-magnets, the circuits of which are closed or broken by the lateral displacement of the note sheet.

In the form of the device here shown a pneumatic operating mechanism is employed which comprises a casing 21 having flexible side and bottom walls, as indicated at 22 and 23, and provided with a diaphragm or movable partition 24 dividing the interior of the casing into two compartments or chambers 25 and 26. This diaphragm or movable partition is operatively connected to the lever 19, and, in the present instance, has an upwardly extending arm 27 rigidly secured thereto and connected with the lever 19 by a rod 28.

Each chamber 25 and 26 has a conduit or tube 29 communicating therewith and connecting the same with a passage 30 formed in the base 31 upon which the operating mechanism is mounted. These passages 30 are, in turn, connected with a suction pipe 32 which communicates with a suitable suction apparatus which may be of any suitable character, but is here shown as a suction fan 34. The conduits 29 communicate with the passages 30 through valve chambers 35 having flat top and bottom walls. The bottom wall of each valve chamber has therein a port 36 communicating with the corresponding passage 30 and the top wall of the chamber has one or more ports 37 connecting the valve chamber with the atmosphere. A flat disk-like valve 38 is arranged within each valve chamber 35 and normally rests upon the lower wall thereof and closes the port 36. The suction in the passages 30 serves to retain the valve members 38 firmly upon their seats and effectually close communication between the suction pipe and the chambers 25 and 26. With the valve members in this position the chambers are in open communication with the atmosphere through the conduits 29 and ports 37. The valve members 38 are actuated by electro-magnets, which, in the present instance, comprise solenoids 39, to the cores of which are secured the valve stems 40 of the valve members 38. The solenoids 39 are connected in separate circuits 41 and 42 respectively, and each of these circuits

has a circuit breaker and closer which is actuated by the lateral displacement of the note-sheet.

Arranged near each edge of the note-sheet 5 is a movable guide 43, which, in the present instance, constitutes one member of a circuit breaker and closer. This movable member is preferably formed of thin resilient metal and bears gently against the adjacent edge of the note sheet when the latter is in its normal position, *i. e.*, when it is traveling in its proper course with relation to the tracker bar 4. This pressure of the contact members 43 against the opposite edges of the note-sheet would serve to a certain extent to counteract any tendency on the part of the note-sheet to depart from its proper course. Any appreciable diversion of the note-sheet from its true course will, however, move the contact member 43 on that side toward which the note-sheet is diverted into engagement with the fixed contact member 44 of the circuit breaker and closer. These circuit breakers and closers may be of any suitable construction and may be supported from the frame 1 in any suitable manner, but I have here shown the fixed contact member 44 as mounted on one of the side members of the frame 1 from whence it extends inwardly to a point not far removed from the edge of the note-sheet and is then bent rearwardly, as shown at 45, and has rigidly secured to the rear end thereof the movable contact member 43, the two members being insulated one from the other, as shown at 46. The circuit breakers and closers may be located at any suitable points along the edges of the note-sheet where they will be actuated by the lateral displacement of the note-sheet, but, inasmuch as the note-sheet is to be maintained in a predetermined relation to the tracker bar, it is usually desirable to mount the circuit breakers and closers as near the tracker bar as is convenient and I have, in the present instance, shown the circuit breakers and closers so mounted.

The operation of the device will be readily understood from the foregoing description and it will be apparent that should the note-sheet be diverted from its course toward the left, as shown in Fig. 1, the contact member 43 of the circuit breaker and closer on the left-hand side of the note-sheet will be actuated and the circuit 41 closed, thus energizing the electro-magnet 39 which actuates the valve 38 controlling the conduit 29 communicating with the chamber 25 of the pneumatic operating mechanism. The instant this circuit is closed the valve 38 is lifted from its seat on the lower wall of the valve chamber and seated against the upper wall of the valve chamber, thereby cutting off the conduit 29 from the atmosphere and connecting the same with the passage 30 and 130

the suction pipe 32. The air suction apparatus when placed in communication with the chamber 25 will partially exhaust the air within the same and reduce the pressure on the adjacent side of the diaphragm or movable partition 24 below atmospheric pressure. The other chamber 26 being in communication with the atmosphere, the adjacent side of the diaphragm 24 will be subjected to atmospheric pressure and, consequently, the diaphragm will be moved toward the chamber 25. This movement of the diaphragm rocks the arm 27 and, through the medium of the rod 28, the lever 19 toward the left, thereby shifting the roller 2 toward the right and restoring the note-sheet to its normal position. As soon as the note-sheet has been restored to its normal position the movable contact member 43 will return to its normal position, the circuit 41 will be interrupted and the solenoid 39 will be deenergized and the valve 38 will move into engagement with its seat on the lower wall of the valve chamber, thereby cutting off the chamber 25 from the suction pipe 32 and restoring communication between that chamber and the atmosphere, again equalizing the pressure in the two chambers 25 and 26 and permitting the diaphragm to return to its normal or central position.

The note-sheets used in connection with self-playing instruments vary somewhat in width, and, to adapt the device to use with sheets of different width, I have, in Fig. 3, shown the circuit breakers and closers adjustable toward and away from each other. As shown in this figure the roller 47 is journaled on pintles 48 mounted in the frame 1. The roller is straight throughout its length and has adjustably supported near each end thereof a plate 49 extending partially about the roller and forming a flange therefor. The plate or flange 49 is mounted on rods 50 which are rigidly secured to a bar 51. Each of the bars 51 has secured thereto a rod 52 arranged longitudinally to the roller. The adjacent ends of these rods are screw-threaded and are connected one to the other by a turn-buckle 53, by means of which the rods can be adjusted toward and away from each other and the flanges moved longitudinally to the roller 47. The movable contact member 54 of each circuit breaker and closer is mounted on and insulated from the flange or contact member 49 and is arranged along the edge of the note-sheet in a position to be actuated by the lateral displacement of that sheet.

In Figs. 5 and 6 I have shown a similar arrangement of the adjustable flange, but have provided the movable contact member 55 with a slightly different form. In this form of the device the movable contact member is segmental in shape to correspond to

the shape of the flange or plate 49 and has near each end thereof a slot 56 through which extends one of the rods 50 carrying the flange. The central portion of the contact member 55 is curved outward and is arranged near the edge of the note-sheet so that the lateral displacement of the note sheet will move the central portion of the contact member toward the flange 49, the slotted ends of the movable member moving longitudinally to the flange to permit of the lateral movement of the central portion thereof.

It will be obvious that if it should be found desirable manually operated circuit breakers and closers could be inserted in the circuits which control the electro-magnets to enable the shifting mechanism to be controlled by the operator, as indicated at 57 and 58 in Fig. 1. These manually operated circuit breakers and closers may be employed as auxiliary to the sheet-operated circuit breakers and closers or may be independent thereof.

It will be understood that the mechanism herein shown and described is so shown and described for the purpose of illustration only and that the functions of the several parts of this mechanism could be performed by mechanism other than that here shown without departing from the spirit of my invention, and, I, therefore, wish it to be understood that I do not desire to be limited to the details of construction shown and described, for obvious modifications will occur to a person skilled in the art.

Having thus fully described my invention, what I claim as new and desire to secure by Letters Patent, is:—

1. In a device of the character described, the combination, with a traveling sheet, a supporting roller for said sheet, and a shifting device to impart lateral movement to said sheet, of controlling means for said shifting device curved about the periphery of said roller and controlled by the lateral displacement of said sheet.

2. In a device of the character described, the combination, with a traveling sheet, a supporting roller for said sheet, and a shifting device to impart lateral movement to said sheet, of controlling devices curved about the periphery of said roller near the respective ends thereof and controlled by the lateral displacement of said sheet.

3. In a device of the character described, the combination, with a traveling sheet, a supporting roller for said sheet, and a shifting device to impart lateral movement to said sheet, of controlling devices curved about the periphery of said roller near the respective ends thereof and controlled by the lateral displacement of said sheet, and means to simultaneously adjust said devices relatively one to the other.

4. In a device of the character described, the combination, with a traveling sheet, a roller over which said sheet travels, and a shifting device operatively connected to said sheet to move the same laterally in either direction, of electro-magnets controlling said shifting device, circuit breakers and closers to close the circuit through the respective electro-magnets, mounted on opposite sides of said sheet, and curved about the periphery of said roller controlled by the lateral displacement of said sheet.

5. In a device of the character described, the combination, with a traveling sheet, and a shifting device therefor, of a casing, a diaphragm movably mounted in said casing and dividing the same into two chambers, means for operatively connecting said diaphragm to said shifting device, a suction pipe, conduits connecting each of said chambers with said suction pipe, valves controlling said conduits, electro-magnets for actuating said valves, circuits for said electro-magnets, and circuit breakers and closers in said circuits, said circuit breakers and closers being arranged on opposite sides of said traveling sheet and having parts in engagement with the respective edges of said sheet and adapted to be actuated by the lateral displacement thereof.

6. In a device of the character described, the combination, with a traveling sheet, and a shifting lever therefor, of a casing, a partition movably mounted in said casing and dividing the same into two chambers, an arm secured to said partition and operatively connected with said shifting lever,

an air suction pipe, conduits communicating with said chambers, valve chambers connected with the respective conduits and each having ports communicating with said suction pipe and the atmosphere, respectively, a valve member mounted in each of said valve chambers, solenoids having their cores operatively connected to the respective valve members, circuits for said solenoids, and circuit breakers and closers for said circuits, said circuit breakers and closers being arranged on opposite sides of said traveling sheet and each comprising a movable member engaging the adjacent edge of said sheet and adapted to be actuated by the lateral displacement thereof.

7. In a device of the character described, the combination, with two rollers, and a sheet supported by said rollers and adapted to move from one to the other thereof, of a shifting device for said sheet, electrically actuated devices for controlling the movement of said shifting device, circuits for said electrically actuated devices, circuit breakers and closers for said circuits, said circuit breakers and closers being supported at the opposite ends of one of said rollers, and mechanical connections between said circuit breakers and closers for adjusting the same simultaneously toward and away from each other.

In testimony whereof, I affix my signature in presence of two witnesses.

ERNST G. ANDERSON.
